US0D1056840S

(12) **United States Design Patent** (10) Patent No.: **US D1,056,840 S**
(45) Date of Patent: ** Jan. 7, 2025

(54) **CONVERTER**

(71) Applicant: **Shenzhen Hanyang Technology Co., Ltd.**, Shenzhen (CN)

(72) Inventors: **Yang Huang**, Shenzhen (CN); **Wenbang Li**, Shenzhen (CN)

(73) Assignee: **Shenzhen Hanyang Technology Co., Ltd.**, Shenzhen (CN)

(**) Term: **15 Years**

(21) Appl. No.: **29/909,371**

(22) Filed: **Aug. 4, 2023**

(51) LOC (15) Cl. **13-02**

(52) U.S. Cl.

USPC **D13/110**

(58) **Field of Classification Search**

USPC D13/110, 103, 106, 107, 112, 113, 116

CPC H02J 7/0044; H02J 7/342; H02M 7/003

(57) **CLAIM**

The ornamental design for a converter, as shown and described.

DESCRIPTION

FIG. 1 is a front, left and top perspective view of a converter showing our new design;

FIG. 2 is a rear, right and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dash-dash broken lines in the drawings depict the portions of the converter which form no part of the claimed design.
